IGNITION SYSTEM.

1,322,672.

Specification of Letters Patent. Patented Nov. 25, 1919.

Application filed October 29, 1917. Serial No. 199,133.

To all whom it may concern:

Be it known that I, ALFRED C. DE LORME, a citizen of the United States, residing at East Orange, in the county of Essex and 5 State of New Jersey, have invented certain new and useful Improvements in Ignition Systems, of which the following is a specification, such as will enable others skilled in the art to which it appertains to make 10 and use the same.

This invention relates to an electric ignition system suitable for internal combustion engines and more particularly to engines of large size, such as those used in 15 aero and hydro-planes, and motor boats, etc. In large engines of this character special means must be resorted to for the purpose of starting them. In the case of aeroplanes, it is the common practice to either prime the 20 engine by introducing fuel through pet cocks or by seizing the propeller blades and turning the engine over by hand thus causing the pistons to draw in fuel charges, after which a separate source of ignition 25 other than the main or service ignition which is permanently associated with the engine, is operated in any suitable manner to deliver a spark in one of the cylinders having a fuel charge under more or less 30 compression.

In many instances on stopping an engine, enriched mixtures are taken into the engine cylinders which will remain for quite a period of time under partial compression, 35 which may be ignited by the auxiliary or starting ignition and the engine will start up without having to resort to the above described means. In fact, starting on compression is an old procedure and need not 40 be described further herein.

Various schemes have been proposed for this ignition work including a service magneto and a starting magneto, or a service magneto or a battery and vibrating coil in 45 place of the starting magneto, the starting magneto or coil being connected to the service magneto distributor through a trailing brush, or a starting magneto of the low tension type may be used, the same being connected to the primary of the service magneto thereby using the armature of the service magneto as an induction coil. My invention is directed to ways and means of 50 introducing the auxiliary or starting source 55 of ignition current through the main dis-

tributer in such a way that the structure will be simple and cheap, yet efficient.

This and other objects will be apparent to one skilled in the art after considering the principles set forth in this specification and 60 attached drawings, wherein Figure 1 is a side elevation of the magneto used for the service ignition, the distributor device and other parts associated therewith being shown in section. 65

Fig. 2 is an end view of part of the distributor device but with the central portion removed.

Fig. 3 is a diagrammatic view of the service and starting ignition machines in circuit 70 with one of the distributor elements.

In the drawings like numbers refer to corresponding parts in the different views. 1 illustrates a magneto having a driving shaft 2, breaker box 3 and a distributing 75 device consisting of three elements, a block 4, a distributing member 5 and a connector 6. The block has a series of electrical contacts 7 to 14 inclusive, eight being shown although this number may be varied to suit 80 the number of engine cylinders. The said contacts are suitably mounted in the distributor block 4 and holes 15 to 22 are provided with wires to be connected between the contacts 7 to 14 inclusive and their respective spark plugs on the engine cylinders. For the sake of brevity the engine cylinders and spark plugs are not shown as these are 85 old and well known devices.

Mounted in the interior of the block is 90 an annular ring 23 which has two ears 24 and 25 projecting away from the ring so as to form flat contact surfaces for the engagement of brushes 26 and 27. In the type of magneto shown in Fig. 1 the induction 95 coil 28, having the usual primary and secondary windings P and S, is mounted in the arch of the magnets and has its secondary connected by suitable connecting means to the brush 27 mounted in the connector 6 100 which has on its forward end a boss 29 supported in the recess 30 and its rear end held in a collar 31 attached to the frame of the magneto. The rear end is preferably squared at 32 to prevent the connector 6 105 from turning. The block 4 carries the terminal contact 33 having a thumb nut 34 on the exterior part of the block for the purpose of receiving a wire from the source of starting current. The connector 6 carries 110

- a brush 35 which with 26 constitutes a pair to complete a circuit from the contact 33 to the ear contact 24 as shown in Fig. 1. It will be understood that the positions of the brush and coöperating surface contact may be reversed in position and I do not wish to be limited to the particular arrangement shown. This also applies to the brush 27 and coöperating ear contact 25.
- 10 Block 4 is held to the magneto 1 by any suitable means such as a housing 36 and studs 37 only one of which is shown, but the mounting must be such that block 4 is adjustable, it having a lug 38 for the purpose 15 of receiving adjusting means. The lug 38 is shown in dotted lines in its alternate position in Fig. 2, it being understood that the entire block moves with the lug 38 although for the purpose of clarity this adjusted position of the parts carried by the block is 20 not shown.

The distributing member 5 is suitably attached to the gear wheel 39 that is adapted to be driven by a pinion operated by shaft 25 2 in the usual manner. The distributing member 5 carries a brush 40 that is in permanent engagement with the collector ring 23. Electrically connected with the brush 40 is another brush 41 that is adapted to 30 engage spark plug contacts 7 to 14 inclusive as the distributing member 5 rotates in synchronism with the shaft 2.

As shown in Fig. 3 the service magneto 1 has the usual cam 42 and breaker arm 43 operating in connection with the primary P. The secondary S is connected through the rear end of the connector 6 in any suitable manner with brush 27 as heretofore described. In the diagrammatic arrangement 40 of Fig. 3 the contact 33 is omitted and the secondary s is shown connected directly to the brush 35 carried by the connector 6. As shown in this figure, the auxiliary or starting source of current is illustrated as an 45 other high tension magneto having primary winding p and secondary s, as mentioned, breaker arm 44 and cam 45, although a battery and coil or equivalent devices may be used for furnishing the starting current.

50 In Figs. 1 and 2 the starting contact 33 is shown in engagement with brush 35 and the brush 26 is in contact with contact ear 24. With the distributor block in this position the brush 27 will be in the position shown 55 in Fig. 2; now when the block is moved to the position where the lug 38 is shown in dotted lines, the terminal 33 is moved to the dotted position shown and the contact ear 25 will be carried forward to where it 60 is shown in dotted position in Fig. 2, thus placing the brush 27 in connection with the contact 25 from which it will be seen, by reference to Fig. 3, that the service magneto is then connected with the collector 65 ring 23 and hence service magneto current

will be distributed by the distributing member 5 to the various contacts 7 to 14 as previously described.

From the foregoing description it will be seen by shifting the part of the entire distributor device that carries the spark plug contacts, that the starting ignition is delivered to the main or service distributor brush in a retarded position, that is, at a later point referred to the piston stroke than the 75 main ignition machine which is timed usually somewhat ahead of dead center or at the point to get maximum efficiency from the engine at its working speed as in many cases a fixed spark ignition machine is used. 80 Whether or not a fixed spark machine be used or one with an advance lever, the starting current is applied to a spark plug that is in a cylinder in which the piston has gone over dead center. By utilizing the 85 same distributor brush for both starting and ignition current in preference to a trailing brush of the same kind as the main brush for the starting current, I cut the brush wear and its attendant troubles in half. 90 Where a jump spark contact is used in the distributor for the trailing brush arrangement, much heat is taken out of the spark in the engine cylinders which is highly essential in starting due to the poor mixture, 95 etc., and hence by using a "wipe" contact in the distributor I eliminate this objectional feature.

While I have shown the distributing device as a part of the service ignition machine yet I wish it to be understood that this distributing device may be placed on any part of the engine, my invention not being limited to its being placed directly on the service ignition machine. As a matter 100 of fact in certain classes of ignition work the distributing devices are mounted on engine members instead of on the magneto. This is almost a necessity where the cylinders are placed at angles of 45 degrees and 110 the spark plug contacts carried by the distributor block are irregularly spaced and hence more room is required to get the contacts that are nearest together far enough apart so that the distributing brush will not 115 leave a connecting trail between the adjacent contacts and the spark jump from one to the other.

As shown herein, the block is adapted to be placed either on the magneto or on the 120 engine. It is also to be understood that what is ordinarily called the block may be held stationary and another part having the spark plug contacts mounted thereon may be movable on the block. My invention 125 includes all such modifications and it will be apparent that numerous other changes may be made in the various details without departing from the spirit of my invention or the scope of the appended claims. 130

Having thus described my invention what I claim is:—

1. In an ignition system for internal combustion engines, the combination of a service magneto, a distributor block supporting contacts adapted to be connected to the engine sparking devices, a distributing member associated with said block and contacts, a starting magneto, means for shifting the position 5 of said block, and means to connect either the starting or service magneto to said distributing member when said block is shifted for the purpose described. 70
  2. In an ignition system for internal combustion engines, the combination of a source of service sparking current, a distributor block supporting contacts adapted to be connected to the engine sparking devices, a distributing member associated with said block 15 and contacts, a source of starting sparking current, means for shifting the position of said block and means to connect either the starting or service source of sparking current to said distributing member when said block is shifted for the purpose described. 80
  3. In an ignition system for internal combustion engines, the combination of a service magneto having a generating winding and a distributor block mounted thereon, said block 20 carrying a plurality of contacts adapted to be connected to the engine spark plugs, a service contact on said block adapted to be connected to the said generating winding, a distributing member adapted to rotate within 25 said block and normally connected with said service contact, a starting contact on said block, a starting magneto having a generating winding adapted to be connected to said starting contact, said contacts carried 30 by a block being shiftable to connect either the starting or service contact into circuit with said distributing member for the purpose described. 90
  4. In an ignition system for internal combustion engines, the combination of a service ignition machine having a generating winding and a distributor block mounted thereon, said block carrying a plurality of contacts adapted to be connected to the various engine 35 spark plugs, a service contact on said block adapted to be connected to said winding, a distributing member adapted to rotate within said block, a starting contact in said block, a source of starting ignition current adapted 40 to be connected to said starting contact, said contacts carried on the block being shiftable to connect either the starting contact and the source of starting ignition current or the service contact and service ignition machine 45 into circuit with said distributing member for the purpose described. 100
  5. In an ignition system for internal combustion engines, the combination of a service magneto, a distributor block supporting contacts adapted to be connected to the engine 50
- sparkling devices, a distributing member associated with said block and contacts, a starting magneto, means for shifting the position of said contacts, and means to connect either the starting or service magneto to said distributing member when said contacts are shifted for the purpose described. 105
6. In an ignition system for internal combustion engines, the combination of a source of service sparking current, a distributor block supporting contacts adapted to be connected to the engine sparkling devices, a distributing member associated with said block and contacts, a source of starting sparking current, means for shifting the position of said contacts and means to connect either the starting or service source of sparking current to said distributing member when said contacts are shifted in position for the purpose described. 110
7. In an ignition system for internal combustion engines, the combination of a distributing device consisting of a block carrying contacts adapted to be connected to the engine sparkling devices, a rotary distributing member and a connector carrying contacts; a service ignition machine having a generating winding connected with one of said connector contacts, a starting ignition machine having a generating winding connected with another of said connector contacts, means for shifting the position of said contacts carried by the block for connecting either of said connector contacts in circuit with said rotary distributing member 115 whereby either the service machine or starting machine is connected to the engine cylinders. 120
8. In an ignition system for internal combustion engines, the combination of, a distributing device consisting of; a block carrying contacts adapted to be connected to the engine spark plugs, a rotary distributing member and a connector carrying contacts; a source of service sparking current adapted to be connected with one of said connector contacts, a source of starting sparking current adapted to be connected with another of said connector contacts, means for shifting the position of the contacts carried by the block for connecting through said connector contacts and rotary member either the service or starting source of sparking current to the engine spark plugs for the purpose described. 125
9. In an ignition system the combination of a distributing device consisting of; a block carrying contacts adapted to be connected to spark plugs and an annular collector ring having two contact ears connected to said ring but spaced apart from each other, a rotary distributing member carrying a brush running on said collector ring and a second brush electrically connected to the first and adapted to contact 130

- with said spark plug contacts carried by the block and a connector having brushes adapted to contact with said ears; a source of service sparking current adapted to be connected to one of said connector brushes, a source of starting sparking current adapted to be connected to the other of said connector brushes and means for shifting said block whereby said connector connects either 10 the service or starting source of sparking current to said distributing member for the purpose described.
11. In an ignition system, the combination of a service ignition machine having 15 a generating winding and a distributing device consisting of; a distributor block having spark plug contacts, a rotary distributing member and a stationary connector; of a source of starting ignition current with 20 means for connecting either one or the other of said sources of current in circuit with said spark plug contacts, said means consisting of a collector ring in a movable block, contact ears connected to the ring, 25 a set of brushes in electrical connection, and a separate third brush carried by the stationary connector, said third brush being adapted to be connected to one of said ears and to the winding of the service 30 machine, said set of brushes adapted to be connected to the other contact ear and source of starting current, brushes in electrical contact with each other carried by said rotary distributor and adapted to engage said 35 collector ring and spark plug contacts respectively as described.
12. In an ignition system, the combination of a service ignition machine having primary and secondary windings, a distributing 40 device attached to said machine having; an adjustable block, a rotary distributing member and a stationary connector; said block carrying a plurality of contacts adapted to be connected to spark plugs, 45 a collector ring having two angularly displaced contact ears, and a third separate contact, said connector having a front support in said block and a rear end support on the frame of the machine with means 50 for holding the connector stationary, a pair of brushes in electrical contact and a separate brush carried by said connector, said pair of brushes adapted to engage simultaneously one of said ears and the said third 55 contact on the block, said separate brush being adapted to engage the other ear contact when the block is moved to one extreme position at which time the said pair of brushes is not in contact with the separate 60 contact and ear, said rotary member carrying a pair of brushes in electrical contact for connecting said ring to the spark plug contacts, said secondary winding being connected to the separate brush in the connector and a source of starting ignition 65 current connected to said separate contact on the block, as and for the purpose described.
13. In an ignition system, the combination of a service ignition machine having primary and secondary windings, a distributing 70 device attached to said machine having; an adjustable block carrying contacts adapted to be connected to spark plugs, a rotary distributing member and a stationary connector having one end supported on the block and passing through the rotary member to a rear support on the frame of the machine; a contact member on the block end of said connector connected to the said 75 secondary winding, a separate contact on the block, a source of starting ignition current connected to said separate contact and a pair of contact members on said connector one adapted to engage said separate 80 contact, and means on said block for engaging either the first mentioned contact member on the connector or the other contact member of said pair whereby either the service machine or the source of starting 85 current is placed in circuit with said rotary distributing member for the purpose described.
14. In an ignition system, the combination of a service magneto having a distributing 90 device for distributing current to said plugs, a starting magneto for delivering starting current to said plugs, said distributing device also constituting switching mechanism for switching either the 95 service or starting magneto into the spark 100 plug circuits.
15. In an ignition system for internal combustion engines, the combination of a source of service sparking current timed for maximum running efficiency of said engine, a distributing device for directing said sparking current to the various engine spark 115 plugs, a source of starting sparking current connected to said distributing device, said distributing device being adjustable for 120 selecting the service or starting current and at the same time retard the time of application of the starting current to said spark 125 plugs as and for the purpose described.

In witness whereof, I affix my signature. 125
ALFRED C. DE LORME.
